Charles J. Newell

UNITED STATES PATENT OFFICE.

WILLIAM H. HOVEY, OF BRAZIL, INDIANA.

CHEEK-PLATE FOR DRAW-BARS.

SPECIFICATION forming part of Letters Patent No. 390,231, dated October 2, 1888.

Application filed July 18, 1888. Serial No. 230,297. (No model.)

To all whom it may concern:

Be it known that I, WILLIAM H. HOVEY, of Brazil, in the county of Clay and State of Indiana, have invented new and useful Improvements in Cheek-Plates for Draw-Woods in Railroad-Cars; and I hereby declare that the following is a full, clear, and exact description thereof, reference being had to the accompanying drawings, which form a part of this specification.

My invention relates to the cheek-plates on the draft-wood of railroad-cars; and it consists in the extension of the plates and the longitudinal strain on the bolts.

15 In the ordinary construction of this connection between the draw-bar and the car a strap on the side of the draft-wood has been used. This strap is fastened to the cheek-plate by bolts passing through from side to side. The 20 strain on this plate and the forward and backward movement given to it by the pulling and pushing on the draw-bar in the ordinary use of the car cause it to act on the bolt with a shearing or cutting movement, which destroys 25 the bolt.

The object of my invention is to avoid the cutting and the lateral strain on the bolts, and to convert the lateral strain on the bolts to a longitudinal strain.

30 In the drawings, Figure 1 is a plan view of the cheek-plate and spring. Fig. 2 is a sectional view on the line $x-x$ in Fig. 1. Fig. 3 is a side view of the cheek-plate.

A A are the cheek-plates on the upper side 35 of the draft-wood or spring-timber D. These plates are strengthened by the ribs a a, which also act as a buttress for that part of the plate turned up at its rearward end to form the resistance-plate a'. On the outer edges of the 40 plate wings b are thrown up. The upper edges of these wings are enlarged and perforated through their entire length to form the eye B. These wings also support the outer ends of the resistance-plate. The eye B may 45 be made on the side of the cheek-plate or

wing, if desired. The longitudinal bolt C passes through the eyes in the plates A A, and is screw-threaded at the end which engages with the nut c and the lock-nut c'. The plates f f are perforated to admit the draw-bar and 50 act against the resistance plates a' a'. The buffer-spring E is compressed between these perforated plates, and the draw-bar h (shown in dotted lines) is inserted through the perforated plates and the coiled spring and prop- 55 erly keyed in place.

m m m are studs or dowel-pins projecting from the under side of the cheek-plates and engage with the proper sockets in the draw- 60 wood.

n n n are bolt-holes, through which ordinary bolts are inserted to fasten the cheek-plates to the draw-wood. Four of these cheek-plates are used for each draw-bar, two on the upper side and two on the under side of the draw- 65 wood, or two in front and two in the rear of the spring, and connected by the longitudinal bolts. This construction brings all of the strain of the spring produced by the action of the draw-bar on these longitudinal bolts. 70

What I claim as my invention is—

1. The cheek-plate for draw-woods, provided with eyes for the reception of the longitudinal bolts, in combination with the longitudinal bolts, as and for the purposes set forth. 75

2. The combination of the cheek-plates for draw-woods, provided with the resistance-plates and buttresses, and the eye for the reception of the longitudinal bolt, as and for the purpose described. 80

3. The combination of the cheek-plates in pairs with the longitudinal bolts, as described.

4. The combination of the cheek-plates A, having the ribs a, wings b, eyes B, and resistance-plates a', with the longitudinal bolt C, as 85 and for the purposes described.

WILLIAM H. HOVEY.
